(57) **CLAIM**

The ornamental design for a vegetable slicer, as shown and described.

DESCRIPTION

1. Vegetable slicer

Figure 1.1: A perspective view of a vegetable slicer according to the present invention.

Figure 1.2: A back side view of the vegetable slicer shown in Figure 1.1 with its individual parts shown removed from the vegetable slicer for clarity.

Figure 1.3 : A front side view of the vegetable slicer shown in Figure 1.1 with its individual parts removed from the vegetable slicer for clarity.

Figure 1.4 : A right side view of the vegetable slicer shown in Figure 1.1 with its individual parts removed from the vegetable slicer for clarity.

Figure 1.5 : A perspective view of the vegetable slicer shown in Figure 1.1 with the individual parts removed from the vegetable slicer for clarity.

Figure 1.6: A top side view of the vegetable slicer shown in Figure 1.1 with the individual parts removed from the vegetable slicer for clarity.

Figure 1.7: A bottom side view of the vegetable slicer shown in Figure 1.1 with the individual parts removed from the vegetable slicer for clarity.

Figure 1.8 : A left side view of the vegetable slicer shown in Figure 1.1 with the individual parts removed from the vegetable slicer for clarity. The design relates to a vegetable slicer.
